CLAIM

The ornamental design for an expandable key holder, as shown and described.

DESCRIPTION

FIG. 1 is a perspective view of an expandable key holder, showing my new design;

FIG. 2 is a top view thereof;

FIG. 3 is a bottom view thereof;

FIG. 4 is a front view thereof;

FIG. 5 is a back view thereof;

FIG. 6 is a right side view thereof;

FIG. 7 is a left side view thereof; and,

FIG. 8 is a top view with sides adjusted closer.

The broken line showing of elements in FIGS. 1-8 is included for the purpose of illustrating environmental matter and forms no part of the claimed design.
